(57) **CLAIM**

The ornamental design for the portable phone, as shown and described.

DESCRIPTION

This application claims subject matter that is related to that shown in co-pending U.S. application Ser. No. 29/232,777, filed Dec. 24, 2005, and claiming the benefit of Korean Patent Application Serial No. 30-2004-0039877, filed Dec. 24, 2004.

FIG. 1 is a perspective view of the portable phone showing our design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a front, open view thereof.
